UNITED STATES PATENT OFFICE.

DELBERT J. BRANNING, OF HAWLEY, PENNSYLVANIA.

DESIGN FOR AN ARTIFICIAL FLOWER.

45,985.

Specification for Design.

Patented June 23, 1914.

Application filed April 16, 1914. Serial No. 832,391. Term of patent 3½ years.

To all whom it may concern:

Be it known that I, DELBERT J. BRANNING, a citizen of the United States, and a resident of the city of Hawley, county of Wayne, and State of Pennsylvania, have invented a new, original, and ornamental Design for an Artificial Flower, of which the following is a specification, reference being had to the accompanying drawing, forming part thereof, in which—

Figure 1 is a front elevation of an artificial flower, showing my new design, and Fig. 2 is a side elevation of the same.

I claim:

The ornamental design for an artificial flower, as shown.

DELBERT J. BRANNING.

Witnesses:

GEORGE W. MURPHY,
PERCY C. WELLS.
